UNITED STATES PATENT OFFICE.

HERMANN H. KOELLER, OF ST. LOUIS, MISSOURI.

GRAIN-DRILL.

SPECIFICATION forming part of Letters Patent No. 292,235, dated January 22, 1884.

Application filed January 3, 1882. (No model.)

To all whom it may concern:

Be it known that I, HERMANN H. KOELLER, a citizen of the United States, and a resident of the city of St. Louis, in the State of Missouri, have invented certain new and useful Improvements in Grain-Drills, of which the following is a specification.

This invention consists, first, in the provision, in a grain-drill, of the seed-box bottom arranged in slides, so as to be adjustable in a lateral direction, in order to bring the feed-openings in said bottom more or less over the feeding-cylinders, to regulate the amount of grain discharged; second, in the provision, 15 on the side of the feed-cylinder housing, of a projecting rim for closing the bottom of the feed-openings in seed-box bottom and prevent the escape of grain when the feed of the "drill" is changed, said rim being of a similar diameter to that of the feeding-cylinder; third, in the provision, in connection with the chain-drum that raises the grain-flukes out of the ground, of a lever arranged loosely around 20 said drum, and provided with a spring-pawl 25 which engages in the teeth of a ratchet-wheel secured to the drum, the construction being such that said operating-lever can be swung up into a vertical position when required, so as not to be in the way of the operator when 30 working at the rear of the drill; fourth, in the provision, in connection with each alternate fluke and drag-bar, of a curved lever pivoted at the forward end of the machine, and having connection with an operating-lever within 35 reach of the operator, the construction being such that the flukes can be allowed to assume a "zigzag" position, or be drawn "straight," when desired, as will hereinafter more fully appear; fifth, in certain details of construction, 40 as will hereinafter more fully appear.

In the drawings, Figure 1 is a longitudinal section of a grain-drill having my improvements applied. Fig. 2 is a detail longitudinal section, showing feed-cylinder and connecting parts. Fig. 3 is a transverse section of same. Fig. 4 is a perspective view of one member of the feed-cylinder housing. Fig. 5 is a detail bottom view of the mechanism for laterally adjusting the bottom of the seed-box. Fig. 6 is a detail vertical section of same. Fig. 7 is a detail plan of axle, feed-cylinder driving-shaft, and connections. Fig.

7^a is a sectional view of the same. Fig. 8 is a detail transverse section of same. Fig. 9 is a detached perspective view, showing the locking arrangement between the wheel-hub and its cap or washer. Fig. 10 is a detail perspective view of the hollow thimble or axle for driving-wheels. Fig. 11 is a detail view of supporting-bracket for center of chain-drum. Fig. 12 is a detail side view of the lever mechanism employed for changing the ranks of the grain-flukes in position to allow the flukes to assume a zigzag position. Fig. 13 is a similar view of the same in a position 65 to hold the flukes in a straight position. Fig. 14 is a detail longitudinal section, showing the lever and drum for raising and lowering the grain-flukes. Fig. 15 is a transverse section of the same. Fig. 16 is an enlarged detail 70 longitudinal section of the feed-cylinder, housing, &c.; and Fig. 17 is a detail transverse section of the same, showing in dotted lines the lateral adjustment of the seed-box bottom.

Similar letters of reference indicate like 75 parts in the several views.

Referring to the drawings, A represents the seed-box supported on a suitable frame, as usual.

C C' are the ground-wheels turning on fixed 80 tubular thimbles or axles c², secured to the sides of the drill-frame, as clearly indicated in the drawings.

c is an overhanging flange on said thimble, to prevent access of dirt to the bearing of the 85 axle.

The bottom A' of the seed-box is arranged to slide laterally in the seed-box under cleats a, and upon the flat surfaces on the housings of the feed-cylinders E', (see Fig. 2,) the adjustment being accomplished by a sliding plate, D, arranged in slides D', and having a cam-slot, d, in which engages the pin d' on the bottom A', (see Figs. 5 and 6,) the construction being such that a longitudinal movement of 90 said plate will impart a lateral adjustment to the bottom A'.

d' is thumb-nut for locking the plate D in its required adjustment.

E' are the feed-cylinders, having seed-grooves 100 around their periphery, as shown, which are preferably parallel with the axis. The cylinders turn upon an annular flange, e, of the housing E, as shown, and through a square or

other corner-shaped opening passes the driving-shaft L, common to all the feed-cylinders. e' are inturned flanges on the housing, to prevent the access of grain or dirt between the ends of the feed-cylinder and the faces of said housing.

e² is a circular flange or extension of the housing E, of a diameter equal to that of the feed-cylinder, the purpose of which is to close up the bottom of the feed-openings a' in the seed-box bottom A' when said bottom is adjusted in a lateral direction past the feed-cylinder in adjusting the "feed" of the drill. In each of the feed-openings a' there is arranged a hinged plate or gate, G, which, when in its down position, as shown in full lines in Figs. 2 and 16, rests against the periphery of the feed-cylinder, so as to limit the feed of said cylinder to the amount of grain contained in its seed-grooves. The gates are used in their "down" position in sowing wheat; but when the drill is used for sowing oats they will be turned up into the position indicated in dotted lines in Figs. 2 and 16, so as to leave a large discharge-opening at the front of the housing E.

H are funnels or receivers for receiving the grain discharged by the feed-cylinders, pivoted to ear-lugs h of the housing, as shown, and having hinge-joint connections at h with the conductors H', that convey the grain to the flukes I. The grain-flukes I are connected by drag-bars I' I² to the frame of the drill in the following manner: Each alternate bar I² is connected to a fixed pivot, i, and the remaining bars I² have their ends passed through stirrups eyes i', with a pin, i², to limit their backward movement when in a zigzag position.

These last set of drag-bars I², with their flukes, are drawn straight or into line by the following means:

J is a hand-lever, pivoted at the rear of the drill, and having link-connection j with a curved lever, J', the lower end of which engages a pin-projection on each of said drag-bars, so that by operating the hand-lever J the drag-bars, with their flukes, will be drawn forward into line, and held in such position by a latch, j', engaging a pin on the hand-lever J, to lock it in its "up" position.

The mechanism for turning the chain-drum K, so as to raise and lower the drill-flukes, consists of a ratchet-wheel, k, fixed on said drum, and a lever, K', loosely pivoted on the same, and provided with a spring-dog that engages the ratchet-wheel when it is required to operate the chain-drum. The object of this construction is to permit of said lever being swung into a vertical position out of the way of the operator working at the rear of the drill.

k' is a catch for holding the lever in its up position.

A supporting-bracket is arranged at the center of the chain-drum K, so as to support it at such point and prevent warping, and at the same time form a pivot for the lever J.

The driving-shaft or rod that operates the feeding-cylinders E' is arranged to extend axially through the hubs of the driving-wheels, 7c and is divided into two sections, L L'. The section L is common to all the feed-cylinders, and is capable of a rotation independent of the driving-wheel C, through which it passes. The section L' is fixed to the hub-cap L² by a line-clip, l, and also by its squared portion passing through a similar-shaped orifice in the cap, the said cap in turn being secured to the hub C by lugs l' and recesses l'', (see Fig. 9,) so as to rotate with the same. The positive motion imparted by the driving-wheel C to this shaft-section is imparted to the section L, that drives the feeding-cylinders, by means of a ratchet-clutch, M, in manner indicated in Fig. 7. This ratchet-clutch, in addition to permitting a retrograde movement of the driving-wheel without imparting a corresponding movement to the feeding-cylinders, also permits of the employment of a cam, N, upon the chain-drum K, so that when said drum is operated to lift the grain-flukes out of the ground the cam N will, through the operating bell-crank n, open the ratchet-clutch M automatically, in order to prevent any further movement being imparted to the feeding-cylinders. n' is a spring for holding the clutch members in engagement. The shaft-section L is detachable endwise from the drill, so as to permit of the ready removal and replacement of the grain-feeding mechanism, and it is held in place in the drill by an abutment-collar, O, and set-screw o, so that when the set-screw is loosened the shaft can be drawn out through the tubular axle of the driving-wheel C.

105 P is a cam formed on the collar O for the purpose of driving a suitable feeding device in using the drill for sowing grass-seed.

The peculiar construction of the clutch M is as follows: m is a sleeve secured to the section L' by a pin or rivet, m', and having an inclosing-sleeve over its ratchet-face, as shown. This ratchet-face may have one or more ratchet-projections, as desired. m² is a sliding ratchet-collar having a square bore fitting over the square shaft-section L, and imparting motion to same when the clutch parts are in engagement. The bearing plate or socket m³ for the sleeve m is let into the side of the drill-timbers, in manner indicated in Fig. 7.

Having thus fully described my invention, what I claim as new, and desire to secure by Letters Patent, is—

1. In a grain-drill, the seed-box bottom proper, made laterally adjustable, and provided with a series of feed-openings, in combination with a series of feed-cups and cylinders, stationary in a lateral direction, for the purpose set forth.

2. In a grain-drill, the combination of the laterally-adjustable seed-box bottom A', feed-cylinders E', and cups or housings E, stationary in a lateral direction, and provided with a projecting rim, e², for the purpose set forth.

3. In a grain-drill, the combination of the adjustable plate B, provided with a cam-slot, d, pin or stud d' on the seed-box bottom, and locking-nut d'', as described, and for the purpose set forth.

4. In a grain-drill, the combination of the fluke-raising drum K, on which is secured a notched ratchet-wheel, k, with the lever K', turning loosely around said drum, and provided with a spring locking dog or bar for locking it to said drum, all constructed and arranged as herein described, and for the purpose set forth.

5. In a grain-drill, the combination of the drag-bars I', curved lever J', engaging pin-projections on said bars, link j, and hand-lever J, as described, and for the purpose set forth. 15

In witness whereof, witness my hand this 31st day of December, 1881, at St. Louis, Missouri.

HERMANN H. KOELLER.

In presence of—

ROBERT BURNS,
HENRY BURNS.
